E. D. BELKNAP,
INKING APPARATUS,
APPLICATION FILED DEC. 7, 1915.

1,208,270.

Patented Dec. 12, 1916.

Inventor
Ezra D. Belknap
By his Attorney
A. Parker Smith

UNITED STATES PATENT OFFICE.

EDWIN D. BELKNAP, OF EAST ORANGE, NEW JERSEY.

INKING APPARATUS.

1,208,270.

Specification of Letters Patent. Patented Dec. 12, 1916.

Application filed December 7, 1915. Serial No. 65,568.

To all whom it may concern:

Be it known that I, EDWIN D. BELKNAP, a citizen of the United States of America, residing at East Orange, county of Essex, 5 State of New Jersey, have invented certain new and useful Improvements in Inking Apparatus, of which the following is a specification.

My invention relates to inking apparatus generally, but is more particularly designed for use with stencil cards, or similar stencils.

The most important novel feature of my invention consists of a special form of fountain ink roll which is also shown and described in my pending application Serial No. 836,811, filed May 6, 1914.

The particular embodiment of my invention here illustrated forms a simple and 20 convenient device fitted for transportation and hand operation in stencil printing.

In the drawings: Figure 1 is an isometric view of the entire apparatus. Fig. 2 is a detail perspective view of the novel fountain ink roll which may be used with this and other forms of apparatus, and Fig. 3 is a perspective view of a block of felt from which such ink fountain rolls are cut or stamped in process of manufacture.

Throughout the drawings, like reference characters indicate like parts.

1, is a roll carrying frame provided with a handle 2, and adapted, when in use, to be conveniently held by the operator in the position shown in Fig. 1, so that the impression roller 3, usually made of rubber or faced with rubber and journaled in the lower end of frame 1, can be pressed down upon and rolled over a stencil card or other form of stencil which has been placed over the envelop or other article on which the stenciled characters are to be printed.

4, is the ink fountain roll which forms the most important feature of my invention, 45 and which may be provided with journals 5, formed by the projecting ends of a cylindrical shaft, adapted to pass through the central hole 7, in the roll. This shaft may be journaled in slots 6, in frame 1, which 50 slots are approximately vertical when the apparatus is in operative position, as shown in Fig. 1. These slots may be left open at their upper ends to facilitate the removal and replacement of roll 4. When in use 55 fountain roll 4, rests on impression roller

3, being held by gravity or other means in peripheral contact therewith.

I call the roll 4, an ink fountain roll because it has the capacity for absorbing, holding and subsequently readily yielding up to impression roller 3, a large quantity 60 of ink, sufficient to ink many thousands of stencils without reloading with ink or replacement by a fresh roll. This characteristic of roll 4, is due to its peculiar construction, it being formed of a solid body of fine, 65 highly porous and absorbent felt, the strata or layers of fine felt running in planes at right angles to the axis of the roll as indicated at 8, in Fig. 2. The best method 70 of forming such a roll is to take a sheet or block of suitable felt 9, the thickness of which is equal to the desired length of the roll 4, and stamp or cut out of it a series of cylinders, each of which forms a roll 75 of the desired character.

10, 10, Fig. 3 indicate holes left in the block of felt after a series of rolls 4, have been so cut or stamped out of it. The strata 8, of the felt appear at the edges of the 80 block or sheet.

As a result of the construction and method of production above described each roll 4, is of uniform and homogeneous composition throughout, having a uniform exterior 85 cylindrical surface devoid of seams, and at which the felt layers are presented edge-wise. The roll so formed is perfectly adapted to absorb a large quantity of ink, hold it in mechanical suspension in and between 90 the layers of felt, and yield it up again evenly along the entire length of the roll and around its entire circumference when rotated with light pressure in contact with a suitable impression roller such as is shown 95 at 3.

It is evident that if such ink fountain roll were made by curling a sheet of felt around a core or shaft, or about central opening 7, the strata or layers of felt being 100 then arranged circumferentially about such core or central opening, the felt would be less capable of absorbing ink radially and soaking it into the interior portions, and less capable of readily giving out radially 105 to the exterior cylindrical surface any ink which had been stored in the interior portions of the roll. Furthermore, the abutting ends of such a curled body of felt would form a seam or line along one element of 110

the outer cylindrical surface no matter how carefully they were cemented or otherwise fastened together. Such meeting edges would produce a heavier line of ink across the surface of the impression roller 3, whenever such joint in the felt surface came in contact with the impression roller, and this would in turn be transferred to the surface being stenciled, producing an uneven 10 appearance thereon. My improved fountain roll avoids these difficulties. It presents an absolutely even and uniform surface to the impression roll and transfers an absolutely even film of ink thereto. Furthermore the 15 capillary pores or spaces in and between the layers forming the original felt sheet are arranged radially of the roll so as to freely and evenly absorb a large quantity of ink, and freely and evenly give it out again 20 to the impression roller. Also perfect rolls can be easily and quickly stamped out of the sheet by unskilled labor.

The operation of the complete inking device shown is as follows: The parts being 25 assembled as shown in Fig. 1, the roll 4, having been previously loaded with ink, the operator grasps the handle 2, holding the apparatus in the position shown in Fig. 1, and moves the impression roller 3, over the 30 stencil which has been laid upon the surface to be marked. The fountain roll 4, rests lightly by gravity on the upper surface of impression roller 3, and is rotated by friction therefrom. Capillary action keeps the 35 surface of roll 4, always damp with ink drawn from the interior of the roll where it is protected from evaporation, and this is transferred by contact to the surface of impression roller 3, and by it to the stencil 40 over which the latter is rolled. When the supply of ink in fountain roll 4, is finally exhausted it is lifted out of its bearings in slots 6, recharged with ink and replaced, or a fresh fountain roll is put in position.

Apparatus embodying my invention has 45 been in practical use for some time and I have demonstrated that a fountain roll of the character described will hold enough ink for inking some fifty thousand stencils, and keep the ink moist and ready for such use 50 during many months.

The great advantage of my invention, in addition to its cheapness and convenience, lies in the fact that it replaces the old ink fountain and doctor roll which constituted 55 a general nuisance. The ink from such fountain was easily slopped over in transportation, and in refilling of the fountain. It soon dried up or became gummy, and on account of the bulk of the fountain and for 60 obvious other reasons (such as the necessity for always keeping it level) it could not be used on a small, portable device, of any such character as is here shown. The present invention has overcome all difficulties and 65 solves the problem of the maintenance in service of small stencil printing machines in the hands of the great multitude of unskilled users.

Having described my invention, I claim: 70

1. As an article of manufacture a fountain roll for inking apparatus consisting of an integral cylindrical body of felt in which layers of material composing the felt extend in planes at right angles to the axis of the 75 cylinder.
2. As an article of manufacture a fountain roll for inking apparatus consisting of an integral cylindrical body of felt in which layers of material composing the felt extend 80 in planes at right angles to the axis of the cylinder, said cylinder having an axial bore of relatively small diameter as compared with the external diameter of the cylinder.

EDWIN D. BELKNAP.
